UNITED STATES PATENT OFFICE.

CHARLES N. CORYELL, OF MAMARONECK, NEW YORK.

LIPSTICK CONTAINER.

Application filed December 27, 1923. Serial No. 682,913.

To all whom it may concern:

Be it known that I, CHARLES N. CORYELL, a citizen of the United States, and resident of Mamaroneck, in the county of Westchester and State of New York, have invented certain new and useful Improvements in Lipstick Containers, of which the following is a specification.

The present invention relates to holders for lipsticks or other stick material and the objects of the invention are to provide a device of this character of simple, inexpensive construction and made up of but few and easily assembled parts; which can be produced in an attractive, convenient form and which will operate both to advance and to retract the stick, positively and without twisting or turning the stick.

In the accompanying drawing forming part of this specification, an embodiment of the invention is illustrated wherein the desired results are attained by a novel construction, combination and relation of parts hereinafter described and claimed.

Figure 1 in the drawing is a side view of the holder in closed condition.

Figure 2 is a longitudinal sectional view of the same.

Figure 3 is a view with the cover removed and the lipstick fully extended, the outer casing and the cap being shown in section.

Figure 4 is a cross sectional view as taken on substantially the plane of line 4—4 of Figure 2.

The body of the holder consists of a tubular casing shown in the form of a cylindrical sleeve 5 open at both ends and shouldered at one end at 6 to receive the detachable cap or top 7.

Rotatably engaged within the case is a sleeve 8 having a helical guideway or cam slot 9 formed therein and attached to or carried by the lower end of this cam sleeve there is provided a suitable knob or finger-hold shown as a cap or thimble 10. This cap may be and preferably is a duplicate of the cover cap 7 but unlike that cap it is not intended to be detached and is fixed on the lower end of the cam sleeve, for instance, by forcing it thereover with a drive fit, far enough to substantially meet the lower end of the case at 11 and thus form in effect a relatively rotatable extension completing the lower end of the case.

The helical guide or cam slot operates as a coarse screw for advancing and retracting

the carrier and may consist as shown of a single convolution extended substantially the full length of the sleeve.

The cam or screw sleeve has a rotating fit over and about a guide sleeve 12, within which the stick carrier 13 travels. This guide sleeve is fixed at its upper end to the upper end of the case at 14 and at its lower and has a relatively rotatable connection with the screw sleeve, said connection being shown as a tubular extension 15 on the closed lower end of the guide sleeve extending freely through an opening in the closed lower end of the screw sleeve and turned over after the manner of a tubular rivet to confine these parts against longitudinal separation while permitting the outer sleeve to rotate freely over the inner sleeve.

A non-rotating longitudinal travel of the carrier is effected within the inner non-rotating guide sleeve by constructing said sleeve with a substantially straight longitudinal guide or slot 16 and providing the carrier with a pin or lug 17 which projects through said slot into the screw slot 9 in the outer rotatable sleeve.

In use, after the cover cap is removed, the stick may be projected as far as desired by simply turning the lower cap with respect to the body of the case, rotation being thereby imparted to the screw sleeve, which by engagement with the projecting pin of the carrier traveling in the straight slot in the guide sleeve, shifts the carrier outward without turning the same. A reverse rotation of the handle cap retracts the stick carrier, also without rotating the same. This non-rotation of the stick in its advancing and retracting movements is advantageous in that it prevents rotative rubbing and cutting of the stick against the slotted tube, which would cause gumming of the parts and presents the same side of the stick to the user, instead of twisting the stick with each advancing movement.

The guide sleeve may be fixed to the case in the same manner that the turning cap is fixed on the screw sleeve, that is, by means of a simple drive fit and in order that this connection may be a secure and permanent one, the upper end of the guide sleeve may be slightly thickened or be made of slightly greater diameter, as indicated at 18, so that in forcing the upper end of the case over the end of the guide sleeve, the parts will firmly "seize" and lock together.

In contracting the upper end of the case over the upper end of the helically shouldered sleeve and into engagement with the end of the tubular guide, the same may be brought down to an outside diameter slightly less than that of the lower end of the sleeve so that the thimble-shaped caps when made all of one size may be used interchangeably either as covers or as the operating knobs, those applied to the cases fitting detachably and those applied to the sleeves making rigid engagement therewith. The relative inclination of the slots in the two sleeves is such as to produce an easy sliding movement of the drive lug of the carrier and the swivel connection between the closed lower ends of the sleeves, centers the sleeves one within the other and further insures a smooth positive action of the parts.

20 What I claim is:

1. In a holder of the character disclosed, a case, a sleeve rotatably mounted within said case provided with a helical shoulder, a carrier within said sleeve having a drive lug engaging said helical shoulder, a guide carried by the case for directing the carrier in a substantially straight non-rotative movement within the case upon rotation of the sleeve within the case, means for rotating the helically shouldered sleeve within the case, said guide being a tube fixed at one end to the case and swivelly connected at its opposite end to the rotatable sleeve.

2. In a holder of the character disclosed, a case, a sleeve rotatably mounted within said case provided with a helical shoulder, a carrier within said sleeve having a drive lug engaging said helical shoulder, a guide carried by the case for directing the carrier in a substantially straight non-rotative movement within the case upon rotation of the sleeve within the case, means for rotating the helically shouldered sleeve within the case, caps for said holder, said caps being substantial duplicates of one another and one detachably engaged over one end of the case and the other fixed to the sleeve, at the opposite end of the case.

3. In a holder of the character disclosed, a case, a sleeve rotatably mounted within said case provided with a helical shoulder, a carrier within said sleeve having a drive lug engaging said helical shoulder, a guide carried by the case for directing the carrier in a substantially straight non-rotative movement within the case upon rotation of the sleeve within the case, means for rotating the helically shouldered sleeve within the case, the case being shouldered at its opposite ends, duplicate end caps, one detachably engaged over the shouldered portion at one end of the case as a cover and the other fixed on the sleeve and in rotative relation to the shoulder at the opposite end of the case.

4. In a holder of the character disclosed, a case, a sleeve rotatably mounted within said case provided with a helical shoulder, a carrier within said sleeve having a drive lug engaging said helical shoulder, a guide carried by the case for directing the carrier in a substantially straight non-rotative movement within the case upon rotation of the sleeve within the case, means for rotating the helically shouldered sleeve within the case, the ends of the sleeve and guide being connected by a swivel. 70

5. In a holder of the character disclosed, a case, a sleeve rotatably mounted within said case provided with a helical shoulder, a carrier within said sleeve having a drive lug engaging said helical shoulder, a guide carried by the case for directing the carrier in a substantially straight non-rotative movement within the case upon rotation of the sleeve within the case, means for rotating the helically shouldered sleeve within the case, the guide means and sleeve having closed ends fitting one within the other and swiveled together by a rivet passing through 80 the same. 85

6. In a holder of the character disclosed, concentric relatively rotatable sleeves, one having a substantially straight slot and the other a helical slot, a sliding carrier within the inner sleeve having a lug projecting through the slot therein into the slot in the outer sleeve, said sleeves having closed ends, one inside the other and a pivot stud extending through said closed ends. 90 95

7. In a holder of the character disclosed, concentric relatively rotatable tubular members having angularly related slots and held against longitudinal separation by a swivel connection at one end, a surrounding case having a portion fixedly engaged with the opposite end of the inner member, whereby the same is held non-rotatably to the case, the outer tubular member having a handle at the end where the slotted members are 105 swiveled together and by which the outer member may be rotated within the case and a carrier within the inner slotted tubular member having a drive lug operating in the relatively inclined slots of the two members. 110 115

8. In a holder of the character disclosed, concentric relatively rotatable tubular members having angularly related slots and held against longitudinal separation by a swivel connection at one end, a surrounding case 120 having a portion fixedly engaged with the opposite end of the inner member, whereby the same is held non-rotatably to the case, the outer tubular member having a handle at the end where the slotted members are swiveled together and by which the outer member may be rotated within the case and a carrier within the inner slotted tubular member having a drive lug operating in the relatively inclined slots of the two members, 125 130

the handle for the outer slotted member comprising a cap engaged over the end of said member substantially abutting the end of the case to form a relatively rotatable continuation of the same and a cap for covering the end of the case which is fixed to the inner tubular member.

9. In a holder of the character disclosed, concentric relatively rotatable sleeves, one having a substantially straight slot and the other a helical slot, a sliding carrier within the inner sleeve having a lug projecting through the slot therein into the slot in the outer sleeve, a case enclosing both sleeves and having a shouldered part contracted over the end of the outer sleeve into engagement with the inner sleeve, a cover cap detachably engageable over said shouldered part of the case and a handle cap engaged with the outer sleeve at the opposite end of the case.

10. In a holder of the character disclosed, a case, a carrier in said case, relatively rotatable means within the case for advancing and retracting the carrier and end caps of like construction, one detachably engageable with the case and the other rigidly engaged with the relatively rotatable carrier operating means.

11. In a holder of the character disclosed, relatively rotatable concentric sleeves having

end portions disposed one inside the other and a pivot centrally located in said end portions and swivelly connecting the same, and a carrier within the inner sleeve having a drive lug, the sleeves having relatively inclined slots receiving said lug whereby upon relative rotation of said sleeves the carrier will be shifted therein.

12. As a new article of manufacture, a lip stick having a symmetrical smooth outer casing comprising an intermediate casing sleeve portion and two interchangeable end caps, a holder for a lip stick within said casing, a tube between said holder and the casing, fixed to the casing sleeve and provided with a longitudinal slot, a separate tube having a helical slot therein confined between said fixed tube and the casing and rotatable relative to said casing and fixed tube, a pin on the holder projecting through the longitudinal slot into the helical slot, one of the end caps being engaged as a removable cover on one end of the casing sleeve and the other end cap being engaged with the tube member having the helical slot for rotating the same to feed the holder into and out of the casing in a straight line movement.

Signed at New York, in the county of New York and State of New York, this 19th day of December, A. D. 1923.

CHARLES N. CORYELL.
